US00D813852S

(12) **United States Design Patent** (10) **Patent No.:** **US D813,852 S**
(45) **Date of Patent:** **** Mar. 27, 2018**

(54) **WIFI RANGE EXTENDER**

(71) Applicant: **HANGZHOU TELEHEMS ELECTRONICS TECHNOLOGY CO., LTD.**, Hangzhou, Zhejiang Province (CN)

(72) Inventor: **Lizhou Ni**, Hangzhou (CN)

(73) Assignee: **HANGZHOU TELEHEMS ELECTRONICS TECHNOLOGY CO., LTD.**, Hangzhou (CN)

(**) Term: **15 Years**

(21) Appl. No.: **29/573,415**

(22) Filed: **Aug. 5, 2016**

(30) **Foreign Application Priority Data**

Feb. 5, 2016 (CN) 2016 3 0043032

(51) **LOC (11) Cl.** **14-03**

(52) **U.S. Cl.**

USPC **D14/240**; D14/358

(57) **CLAIM**

The ornamental design for a WiFi range extender, as shown and described.

DESCRIPTION

FIG. 1 is a front, left-side, bottom perspective view of the WiFi range extender;

FIG. 2 is a rear, right-side, top perspective view thereof;

FIG. 3 is a front elevational view thereof;

FIG. 4 is a top plan view thereof;

FIG. 5 is a right-side elevational view thereof;

FIG. 6 is a left-side elevational view thereof;

FIG. 7 is a rear elevational view thereof; and,

FIG. 8 is a bottom plan view thereof.

The broken lines depict unclaimed portions of the WiFi range extender, and thus form no part of the claimed design.

1 Claim, 8 Drawing Sheets
